UNITED STATES PATENT OFFICE

135,256

DESIGN FOR AN ULTRAVIOLET STERILIZER

Robert A. Hrabak, Lakewood, Ohio, assignor to
The Art Metal Company, Cleveland, Ohio, a cor-
poration of Ohio

Application August 12, 1942, Serial No. 107,917

Term of patent 14 years

To all whom it may concern:

Be it known that I, Robert A. Hrabak, a citizen of the United States and a resident of Lakewood, in the county of Cuyahoga and State of Ohio, have invented a new, original, and ornamental Design for an Ultraviolet Sterilizer, of which the following is a specification, reference being had to the accompanying drawings, forming a part thereof.

In said drawings, Fig. 1 is a top plan view of an ultraviolet sterilizer showing my design; Fig.

2 is a front elevational view, the rear being substantially the same; Fig. 3 is a left end elevational view; Fig. 4 is a right end elevational view; Fig. 5 is a bottom plan view; and Fig. 6 is an enlarged cross-sectional view on the line 6—6, Fig. 2.

I claim:

The ornamental design for an ultraviolet sterilizer, substantially as shown.

ROBERT A. HRABAK.
